(57) **CLAIM**

The ornamental design for a belay and rappel device, as shown and described.

DESCRIPTION

FIG. 1 is a front, left-side, top perspective view of the belay and rappel device;

FIG. 2 is a left-side elevational view thereof, the right-side elevational view (not provided) being a mirror image thereof;

FIG. 3 is a top plan view thereof;

FIG. 4 is a rear elevational view thereof;

FIG. 5 is a front elevational view thereof;

FIG. 6 is a bottom plan view thereof; and,

FIG. 7 is a rear, right-side, top perspective view thereof. The broken lines depict parts of the belay and rappel device that form no part of the claimed design.
